US00D568892S

(12) **United States Design Patent** (10) Patent No.: **US D568,892 S**
 Stabb et al. (45) Date of Patent: **** May 13, 2008**

- (54) **IMAGE FOR A PORTION OF A DISPLAY SCREEN**
- (75) Inventors: **Charles W. Stabb**, Seattle, WA (US); **Donald J. Lindsay**, Mountain View, CA (US)
- (73) Assignee: **Microsoft Corporation**, Redmond, WA (US)
- (**) Term: **14 Years**
- (21) Appl. No.: **29/228,348**
- (22) Filed: **Apr. 22, 2005**
- (51) LOC (8) Cl. **14-04**
- (52) U.S. Cl. **D14/485**
- (58) Field of Classification Search **715/500.1, 715/501.1, 526, 530-31, 539, 708, 711, 717, 715/723, 726, 733, 738, 753, 762, 763-4, 715/767-69, 778-82, 788, 790, 793-94, 715/797-8, 802-10, 835-40, 848-856, 862-63, 715/976, 978; 345/757, 782, 848, 852, 850, 345/809, 837, 798, 752, 163, 156, 537, 474, 345/836, 419, 649, 656, 659, 426, 427, 582, 345/428, 440, 660, 634, 902, 418, 629; D14/485-94; D18/24-33; D20/40, 11; D19/6; D21/324-33; 434/43, 38; 382/305; 400/76; 710/5, 73; 707/102, 2; 463/32, 16; 717/170; 705/26, 705/27**

(57) **CLAIM**

We claim the ornamental design for an image for a portion of a display screen, as shown and described.

DESCRIPTION

FIG. 1 is a front view of an image for a portion of a display screen showing our new design; and,

FIG. 2 is a front view of a second embodiment of an image for a portion of a display screen of our new design.

The unshaded regions in the Figures forms no part of the claimed design. The broken line showing the display screen is for illustrative purposes only and forms no part of the claimed design.

1 Claim, 2 Drawing Sheets
